UNITED STATES PATENT OFFICE.

BENJAMIN H. DIETZ AND ALBERT E. HANSEN, OF CHICAGO, ILLINOIS.

DESIGN FOR A PHONOGRAPH CABINET.

60,648.

Specification for Design. Patented Mar. 21, 1922.

Application filed May 21, 1921. Serial No. 471,499. Term of patent 7 years.

To all whom it may concern:

Be it known that we, BENJAMIN H. DIETZ and ALBERT E. HANSEN, citizens of the United States, and residents of the city of Chicago, county of Cook, and State of Illinois, have invented a new, original, and ornamental Design for a Phonograph Cabinet, of which the following is a specification, reference being had to the accompanying drawing, forming part thereof.

The drawing represents a perspective view of our novel phonograph cabinet design.

We claim:

The ornamental design for a phonograph cabinet, as shown.

BENJAMIN H. DIETZ.
ALBERT E. HANSEN.

Witnesses:

T. H. ALFREDS,
CLARENCE E. MEHLHOPE.
